US00D910043S

(12) **United States Design Patent** (10) Patent No.: **US D910,043 S**
Broughton et al. (45) Date of Patent: ** Feb. 9, 2021

(54) **DISPLAY SCREEN OR PORTION THEREOF
WITH GRAPHICAL USER INTERFACE**

(71) Applicant: **Apple Inc.**, Cupertino, CA (US)

(72) Inventors: **Lee Broughton**, Santa Cruz, CA (US);
Kevin Will Chen, Cupertino, CA (US);
Alan C. Dye, San Francisco, CA (US);
Christopher Wilson, San Francisco,
CA (US); **Eric Lance Wilson**, San
Jose, CA (US)

(73) Assignee: **Apple Inc.**, Cupertino, CA (US)

(**) Term: **15 Years**

(21) Appl. No.: **29/736,975**

(22) Filed: **Jun. 4, 2020**

Related U.S. Application Data

(63) Continuation of application No. 29/682,306, filed on Mar. 4, 2019, now Pat. No. Des. 886,843, which is a continuation of application No. 29/650,891, filed on Jun. 11, 2018, now Pat. No. Des. 842,326, which is a continuation of application No. 29/616,004, filed on Sep. 1, 2017, now Pat. No. Des. 820,300, which is a continuation of application No. 29/567,732, filed on Jun. 11, 2016, now Pat. No. Des. 796,547.
